UNITED STATES PATENT OFFICE.

NATHAN E. LEWIS, OF PLAINFIELD, NEW JERSEY, ASSIGNOR TO THE BABCOCK & WILCOX COMPANY, OF BAYONNE, NEW JERSEY, A CORPORATION OF NEW JERSEY.

SEAL FOR FURNACE CHAMBERS OF BOILERS.

1,402,779.

Specification of Letters Patent. Patented Jan. 10, 1922.

Application filed October 22, 1919. Serial No. 382,522.

To all whom it may concern:

Be it known that I, NATHAN E. LEWIS, a citizen of the United States, residing at Plainfield, county of Union and State of New Jersey, have invented certain new and useful Improvements in Seals for Furnace Chambers of Boilers, of which the following is a specification.

My invention relates to a seal for a furnace chamber and has for its object an improvement in a device of this character. My invention is particularly applicable to boilers of the Babcock & Wilcox type.

With furnace walls such as have hitherto been built, where the furnace wall extended to the boiler tubes and formed a seal with a baffle construction, the difficulty has been experienced that the upper end of the wall has, under the intense heat of the furnace, had a tendency to lean or fall forwardly, thereby breaking the seal and permitting the gases from the furnace chamber to pass through the opening thus formed and impinge against the metal framework of the setting, thereby not only reducing the efficiency of the boiler, because of the failure of part of the gases to pass over the boiler tubes, but warping or otherwise injuring the metal parts of the boiler setting.

In accordance with my present invention an inclined plate extends from the main furnace wall to the headers, or other parts of the boiler, forming a sliding joint therewith, and making a permanent seal for the furnace chamber, the plate preferably being movable independently of the wall.

My invention will best be understood by reference to the accompanying drawings, in which the same parts are indicated by the same reference characters and in which Figure 1 is a longitudinal section through a portion of a steam boiler of the Babcock & Wilcox type embodying my invention; Fig. 2 is a detail view of a section of the boiler shown in Fig. 1 to a larger scale, and Fig. 3 is a view similar to Fig. 1 showing a modification.

Referring now to the drawings and first to Fig. 1, 1 is the setting of a steam boiler comprising front and rear furnace walls 2 and 3, respectively. The rear wall 3 is preferably provided with an opening 4 affording access to the stoker and closed by a door 5.

The stoker, which is here shown as of the underfeed type, is indicated by the reference numeral 6. The water tubes 7 are horizontally inclined in accordance with the usual Babcock & Wilcox construction, and are here shown as comprising an upper bank of tubes 7^a and a lower bank 7^b, though it will of course be understood that my invention is equally applicable to a water tube boiler in which the water tubes are not so divided. In the construction shown in Fig. 1 the lower bank of tubes 7^b comprises only the lower row of tubes. The tubes 7^a of the upper bank are connected to downtake headers 8, and to uptake headers 9, while the lower bank 7^b is connected to a box or header 10 which is nipped to the header 8, as at 11, the other end of the tubes 7^b being connected to a box or header 12 nipped to the header 9, as at 13. A mud drum 14 is located beneath the header 10 and is nipped thereto as at 15. The baffle construction for directing the furnace gases across the boiler tubes comprises a roof baffle 16 extending rearwardly from the header 10 above the lower bank of water tubes 7^b and also comprises a vertical section 17 extending from the rear end of the roof baffle 16 across the upper bank of tubes 7^a and across the secondary combustion chamber 18 which is formed between the lower and upper banks of tubes.

In accordance with my present invention an inclined plate 19 extends upwardly from the main furnace wall 2 and leans against boiler parts, here illustrated as the header 10, and forms a sliding joint therewith, and makes a seal for the furnace chamber between the upper end of the wall 2 and, as the roof baffle 16 engages the header 10, the roof baffle 16. This sliding joint formed between the plate and the header of the boiler is an important feature of my invention, as when the boiler is heated, the lowermost ends of the downtake headers expand downwardly through the fact that the boiler is suspended from above. The action of the heat on the furnace brickwork also tends to raise the plate or plates forming the seal so that altogether there may be a substantial relative movement between the two parts. The lower end of the plate 19 is seated on a member that is stationary with reference to the boiler setting, this member in Fig.

ures 1 and 2 comprising an angle iron 20 which is secured by a bolt or bolts 21 and nuts 22 to the metal framework of the setting so that the bottom of the plate is pivotally mounted on a stationary member and can move forwardly or backwardly thereon.

In the form of my invention here illustrated, the plate 19 and the parts including the mud drum to the rear of the same, are protected by an auxiliary wall 23 which extends upwardly from the upper end of the main furnace wall 2 substantially to the tiling surrounding the front ends of the boiler tubes 7^c, a space being formed between the two which is filled with a yielding material 24, such as asbestos. A layer of heat-insulating material, such as magnesia, 25, is also preferably interposed between the auxiliary wall 23 and the plate 19.

In Figure 3 of the drawing I have shown the lower end of the plate 19 seated in a stationary drip pan 26 on the top of the main wall 2. In this figure I have indicated parts corresponding to those of Figures 1 and 2, but which are slightly modified, by corresponding reference characters with the character "a" appended. The wall 2 is in this form provided with a tile lock 27 similar to that illustrated in an application of David S. Jacobus, Serial No. 90,058, which was filed in the Patent Office on or about April 10, 1916. In the form here shown the lower bank of water tubes 7^c comprises the two lower rows.

It will be apparent, in accordance with my invention, the plate 19 will always form a seal between the upper end of the wall 2 and the headers 10 or other boiler parts, even where the auxiliary wall 23 when such is used, leans or falls forwardly away from the plate 19. Such a seal is especially useful where underfeed stokers are used, and where at the high ratings that must often be carried, the pressure within the furnace may exceed the atmospheric pressure through the operation of the forced blast used in connection with the stoker, that is, there may be a plus pressure within the furnace instead of a minus pressure or draft suction.

What I claim and desire to secure by Letters Patent of the United States is:—

1. In combination with a steam boiler of the water tube type, a furnace comprising a wall, and a plate extending upwardly from said wall and movable independently thereof and forming a sliding joint with boiler parts.

2. In a boiler of the water tube type having vertically extending downtake headers, a furnace wall below the headers, and a plate extending upwardly from said wall and movable independently thereof and forming a sliding joint with said downtake headers.

3. In combination with a steam boiler of the water tube type, a furnace comprising a

wall, and a pivoted plate extending upwardly from said wall and forming a sliding joint with boiler parts to form a seal for the furnace chamber.

4. In combination with a steam boiler of the water tube type, a furnace comprising a wall, and a plate extending upwardly from said wall and movable independently thereof and forming a sliding joint with boiler parts, said plate forming a seal for the furnace chamber.

5. In combination with a steam boiler of the water tube type, a furnace comprising a wall, and a plate extending upwardly from said wall and leaning against the headers of the boiler and forming a sliding joint therewith to make a seal for the furnace chamber.

6. In combination with a steam boiler of the water tube type, a furnace comprising a wall, and a plate extending upwardly from said wall and leaning rearwardly against a header and forming a sliding joint therewith, said plate forming a seal for the furnace chamber.

7. In combination with a steam boiler of the water tube type, a furnace comprising a wall extending substantially to the boiler tubes and comprising a main wall and an auxiliary wall leaning rearwardly, and a plate at the rear of the auxiliary wall but separate therefrom, said plate forming a sliding joint with boiler parts.

8. In a steam boiler of the water tube type, a furnace comprising a wall, boiler tubes located above and exposed to said furnace, and means for sealing the space between said wall and the lowermost tubes comprising a plate extending upwardly from said wall and movably independently thereof and slidably engaging boiler parts.

9. In combination with a steam boiler of the water tube type, a furnace comprising a wall, and a plate extending upwardly from said wall and forming a sliding joint with a header, and a roof baffle extending rearwardly from said header.

10. In combination with a steam boiler of the water tube type, a furnace comprising a wall extending substantially to the boiler tubes and comprising a main wall and an auxiliary wall leaning rearwardly, and a plate at the rear of the auxiliary wall but separate therefrom and forming a support for said plate forming a sliding joint with boiler parts.

11. In a water tube boiler and its setting, a furnace chamber enclosed at least in part by a furnace wall, water tubes located above said furnace chamber, some of the lowermost tubes being exposed to said chamber for substantially their entire length, headers to which said tubes are connected, and means for sealing the space between said wall and said tubes comprising a plate extending up-

- wardly from said wall and forming a sliding joint with headers of the boiler.
12. In a water tube boiler and its setting, a furnace chamber enclosed at least in part by a furnace wall, water tubes located above said furnace chamber, some of the lowermost tubes being exposed to said chamber for substantially their entire length, headers to which said tubes are connected, and means for sealing the space between said wall and said tubes comprising a plate extending upwardly from said wall short of said tubes and forming a sliding joint with headers of the boiler.
13. In a water tube boiler and its setting, a furnace chamber enclosed at least in part by a main furnace wall, water tubes located above said furnace chamber, some of the lowermost tubes being exposed to said chamber for substantially their entire length, headers to which said tubes are connected, means for sealing the space between said wall and said tubes comprising a plate extending upwardly from said wall and forming a sliding joint with headers of the boiler, and an auxiliary wall resting on said main wall and leaning against said plate.
14. In a water tube boiler and its setting, a furnace chamber enclosed at least in part by a main furnace wall, water tubes located above said furnace chamber, some of the lowermost tubes being exposed to said chamber for substantially their entire length, headers to which said tubes are connected, and means for sealing the space between said wall and said tubes comprising a plate extending upwardly from said wall and leaning against the headers of the boiler.
15. In a water tube boiler and its setting, a furnace chamber enclosed at least in part by a main furnace wall, water tubes located above said furnace chamber, some of the lowermost tubes being exposed to said chamber for substantially their entire length, headers to which said tubes are connected, means for sealing the space between said wall and the lowermost tubes comprising a plate extending upwardly from said wall and leaning against boiler parts.
16. In a steam boiler and its setting, a furnace chamber enclosed at least in part by a furnace wall, an underfed stoker for said furnace, boiler tubes located above said furnace chamber, some of which are exposed for substantially their entire length to said chamber, and means for sealing the space between said wall and the lowermost tubes comprising a plate extending upwardly from said wall and leaning against boiler parts.
17. In a steam boiler and its setting, a furnace chamber enclosed at least in part by a furnace wall, an underfeed stoker for said furnace, boiler tubes located above said furnace chamber, some of which are exposed for substantially their entire length to said chamber, means for sealing the space between said wall and the lowermost tubes comprising a plate extending upwardly from said wall and leaning against boiler parts, and an auxiliary wall resting on said furnace wall and leaning against said plate.
- In testimony whereof I have hereunto signed my name in the presence of two subscribing witnesses.
